CLAIM

The ornamental design for a display device, as shown and described.

DESCRIPTION

FIG. 1 is a front perspective view of the display device showing my new design, wherein the display device is in an unfolded state with the heads up display extended;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the display device in an unfolded state with the heads up display folded onto the rear;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof;

FIG. 15 is a front perspective view of the display device in a folded state with the heads up display folded onto the front;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

(Continued)

The broken lines indicate unclaimed portions of the article that form no part of the claimed design.

1 Claim, 21 Drawing Sheets
